UNITED STATES PATENT OFFICE

JOSEPH F. MERKEL, OF ROCHESTER, NEW YORK, ASSIGNOR TO GENERAL RAILWAY SIGNAL COMPANY, OF ROCHESTER, NEW YORK

ILLUMINATED TRACK DIAGRAM

Application filed March 18, 1929. Serial No. 348,026.

This invention relates to interlocking plants for railroads and more particularly to an illuminated track diagram for giving visual indication of the position of the trains within the territory over which a particular plant may have control.

In an interlocking plant, it is necessary that the operator should have accurate information regarding the position of all 10 trains within his territory. In order to do this, a diagram of the track layout over which he has control is usually mounted before him with some means of indicating on the diagram the position of the trains which 15 have entered that particular territory. Such a diagram should be easily read at a distance of several feet, as well as giving recognizable indication of the position of the trains automatically. The diagram panel upon 20 which the indicating means is mounted, must be of an insulating material, as well as being a rigid support.

Illuminated track diagrams, with which I am familiar, have formerly been made 25 either by pasting blue prints to an insulated back ground, or by painting the track layout upon a wood back-ground. In either case, the diagram becomes dull and smeared by repeated cleaning of the surface, which 30 is necessitated by the accumulation of dust and dirt upon the face of the panel, while during the summer season an added source of trouble is given by the bugs which are attracted by the indicating lamps. Furthermore, 35 if some transparent covering be used for the protection of the prints or painting, it too, is soon worn off or chemically dissolved by the cleaning fluids used.

With the above and other considerations 40 in mind, it is proposed in accordance with this invention, to provide an illuminated track diagram with a panel which serves the two-fold purpose of providing a clearly visible diagram which has a transparent surface 45 covering, which is impervious to ordinary chemical solutions, and which provides a rigid insulating panel upon which the electrical indicating means may be mounted.

One object of this invention is to provide 50 an illuminated track diagram which will

meet with the above mentioned requirements and others, as will be in part apparent and in part pointed out as the description of one particular embodiment of the invention progresses.

In describing the invention in detail, reference will be made to the accompanying drawings, in which:—

Fig. 1 is a front elevation of an illuminated track diagram, showing the panel with the diagram super-imposed, the indicating lenses, and the outside frame work;

Fig. 2 is a cross section of Fig. 1 taken on the line 2—2, looking in the direction of the arrows, and showing in detail the construction of the illuminating indicators and the mounting frame work;

Fig. 3 is a detailed cross section of the construction of the diagram panel.

Referring now to the drawings, in one specific form of an illuminated track diagram shown in Fig. 1, sections 1, 2, 3 and 4 of wood or the like form the moulding or border and support for the diagram panel 5, said panel 5 being attached to this moulding 75 by screws 6.

An indicating lens 7, with its metal shell 7^a is located at the center of the track section 8, which is a typical illustration of the other indicating lenses and their respective track sections. The extent of these track sections is shown to be terminated at the points where their continuity ceases, such as, for example, at points 9, 10, and 11. Symbol 12 is located at the entrance to a turn-out switch and represents the normal position of that switch which is typical of the other switches. When the indicating lens at the center of the arrow symbol 14, displays an indication, it represents the fact that the direction of traffic is north, on the right hand, north and south bound track.

Fig. 2 shows a detailed cross-section of the indicating means which comprises the indicating lens 7, the metal receptacle shell 15, the lamp socket 16, the spring 17, and the incandescent bulb 18 in the socket 16. The metal shell 15, has ventilating holes to eliminate the possibility of the bulb getting excessively hot. The diagram panel 5 and 100

moulding is shown mounted as a door which is supported by hinges 20 to a box-like housing. This housing is preferably made of metal plates 21, 22 and 23, riveted to angle iron members 24. The wires 25 and 26 are shown extending from the lamp receptacle 16 to the terminal block 27, and thence through a conduit coupling 28 to their respective control means.

Fig. 3 shows in detail a cross section of the diagram panel, which is subjected to the well known process used in making other resinous phenol formaldehyde condensation products, commonly called bakelite. This panel 5 is to be made up of paper laminae 29 of a sufficient number to make the panel of the required thickness. The top lamina 37 is a Van Dyke print, a photostatic print, or any other type of print or drawing showing the track layout, diagrammatically, with the diagram on the outside. The stacking of paper laminae 29 is then made into a rigid panel by subjecting it to the above mentioned process which may be briefly described below.

The paper laminae are subjected to a vacuum, which extracts all the moisture, after which the stack of laminae is then impregnated under pressure with a phenol formaldehyde resin, which is in the stage A, and due to the fact that the resin at this time is at a high pressure, the paper laminae are impregnated and the spaces between the laminae are filled with the resinous compound, after which the laminae are pressed together under high pressure. The panel is then subjected to a particular temperature which transforms the resinous phenol formaldehyde compound to the stage C, in which state it is then infusible, insoluble in boiling water and ordinary acids, heat resisting, and an electrical insulator of high quality.

After the panel has been carried through the above outlined process a thin covering 38, of the bakelite is left on the outside of the panel, which forms what might be called a perfect protection to the track diagram, which is the top lamina, while the whole panel forms a perfect electrical insulating material and a rigid support for the indicators. Such a panel is practically indestructible under ordinary conditions and will withstand all cleaning fluids and acid fumes from batteries which may be stored in the interlocking tower. The bakelite covering, although having a brownish tinge of the resin, shows the outlines of the diagram very distinctly.

Having thus shown and described one specific embodiment of the present invention in a rather specific manner, it is desired to be understood that this has been done for the purpose of facilitating the disclosure of the invention, and it is desired to be understood that the specific embodiment here given may be adapted and modified without departing from the spirit of the invention.

What I claim is:—

1. An illuminated track diagram for railway signalling systems, comprising, an opaque bakelite impregnated panel built up of laminae and having a drawing of the track lay-out constituting its outer lamina, said drawing being covered with a thin layer of bakelite, lamp indicators supported by, and to the rear of, said panel and insulated thereby, and apertures in the panel in front of the indicators. 70

2. An illuminated track diagram for railway signaling systems comprising an opaque panel formed of paper laminae impregnated with a phenol compound, the outer lamina having a drawing of the track layout thereon, said drawing being covered with a thin layer of the phenol compound, and metal supports for indicating lamps and lenses secured in through holes formed in said panel. 80

3. An illuminated track diagram for railway signalling systems, comprising, an opaque bakelite impregnated panel built up of laminae and having a drawing of the track lay-out constituting its outer lamina, said drawing being covered with a thin layer of bakelite, lamp indicators supported by, and to the rear of, said panel and insulated thereby, and apertures in the panel in front of the indicators, said lamp indicators comprising metal shells, and cushioning springs in the shells for mounting light sources therein. 90

In testimony whereof I affix my signature,
JOSEPH F. MERKEL.
